ARTICLE FEEDING MECHANISM

Daniel Vaughn Waters, Flemington, N. J., and
 Nicholas Zuck, Brooklyn, N. Y., assignors to
 Western Electric Company, Incorporated, New
 York, N. Y., a corporation of New York

Application July 22, 1948, Serial No. 40,068

4 Claims. (Cl. 51—135)

1

This invention relates to article feeding mechanisms for sanding machines of the belt type, and has for its object, the provision of an article feeding mechanism, particularly efficient in moving articles such as synthetic crystals in a given direction relative to the sanding belt of a belt sanding machine under variable pressures and for measured distances to accurately reduce the dimensions of the work.

In the manufacture of synthetic crystals, commercially known as EDT crystals, produced from a solution of ethylene diamine tartrate for use in the communication arts, the mother stones are cut into wafers of given thicknesses and these wafers are to be reduced to final dimensions by moving them in a fixed path into engagement with a sanding belt while covering the working surface of the sanding belt with a liquid such as water which is a solvent for the synthetic crystals.

With the aforementioned object in view, the invention comprises an article feeding mechanism for a belt sanding machine having a sanding belt driven through a given plane, the article feeding mechanism including a table having means thereon to support an article, and parallel links to support the table for movement with the article relative to the sanding belt and to maintain the table at a given angle with respect to the said plane through which the belt travels.

More specifically, the article feeding fixture is mounted on the belt sanding machine wherein the rollers for the sanding belt are positioned to cause the front portion of the belt which travels through the operating or working position to travel in a vertical plane relative to a fixed position backing member for the belt having its guiding face also lying in a vertical plane. The table of the article feeding mechanism supports a magnetic chuck to successively hold article supports at like positions on the table, the article supports being adapted to receive articles such as synthetic crystal wafers. The table is supported by pantograph links on a rocking element, the links permitting movement of the table with the article relative to the sanding belt, assuring maintenance of the table in a plane perpendicular with the sanding belt or that portion of the sanding belt traveling through the working position. The power means for the sanding belt drives a speed reducing unit, which in turn, drives a variable eccentric mechanism connected to the rocking element to rock it together with the table relative to the sanding belt between variable limits. A latch mechanism is provided to hold

2

the table in a loading position, while a variable force embodied in a spring acts to move the table with the article toward the sanding belt a given distance controlled by a variable stop measuring the thickness or dimensions to which the articles or crystal wafers are to be reduced by the sanding process. Also a weight-like unit secured to one of the links and positioned beneath the rocking element counterbalances the structure above the element in its movement toward and away from the sanding belt and also its movement about its axis of oscillation.

Other objects and advantages will be apparent from the following detailed description when considered in conjunction with the accompanying drawings, wherein

Fig. 1 is a front elevational view of the work feeding mechanism mounted on a belt sanding machine, portions of the machine being broken away;

Fig. 2 is a side elevational view of the structure shown in Fig. 1;

Fig. 3 is an enlarged vertical sectional view of the work feeding mechanism, this view being taken along the line 3—3 of Fig. 1;

Fig. 4 is an enlarged fragmentary sectional view taken along the line 4—4 of Fig. 3;

Fig. 5 is an enlarged fragmentary sectional view taken along the line 5—5 of Fig. 1;

Fig. 6 is an enlarged fragmentary sectional view taken along the line 6—6 of Fig. 1; and

Fig. 7 is an isometric view of an article or synthetic crystal wafer.

Referring now to the drawings, attention is first directed to the sanding machine, portions of which are illustrated in Figs. 1 and 2. The sanding machine indicated generally at 10 includes a main housing 11 supporting rollers 12, only one of which is shown in the drawings. The rollers support a sanding belt 14 and cause it to travel whereby the front portion thereof will travel in the direction of the arrow in a vertical plane relative to a backing member 15 whose forward surface 16 lies in a plane parallel with this portion of the sanding belt. The lower pulley 12 is driven through a belt 18 and pulley 19 connected to a power means such as an electric motor (not shown). The pulley 19 of this driving means is mounted on a shaft 20 of the lower roller 12, this shaft also having a pulley 21 mounted thereon. The pulley 21 is connected to an input shaft 22 of a speed reducing unit 23 through a belt 24 and a pulley 25. The speed reducing unit 23 may be of the well-known gear reduction type having an output shaft 26, attention being di-

rected to Figs. 2 and 5. A clutch member 27 is mounted on and keyed to the shaft 26 and supports companion clutch members 28 and 29. The clutch members 28 and 29 have annular friction members 30 and 31 fixed to their inner faces for engagement with the clutch member 27 under variable pressure incorporated in four springs 32 spaced equally about the clutch members. The positions of the springs 32 may be determined by viewing Fig. 1, although the springs are not shown in this figure, they being shown more in detail in Fig. 6. The springs 32 are positioned concentric with screws 34 extending through aligned apertures in the clutch member 29 and the friction member 31 where their threaded ends are receivable in threaded apertures 35 of the clutch member 28. Recesses 36 are formed in the clutch member 28 for the springs 32 and it will be apparent that rotation of the screws 34 in either direction will equally vary the forces in the springs 32 tending to draw the clutch members 28 and 29 toward each other to vary the gripping force between the clutch members 28-29 and the clutch element 27.

An eccentric unit 40 includes a plate 41 fixedly mounted on the clutch member 29 and provided with an aperture 42 to removably receive a pivot 43 of an arm 44. An arcuate elongate aperture 45 is formed in the plate 41 on the opposite side of the axis of the shaft 26 from the aperture 42 to receive a bolt 46 to lock the arm 44 in any selected position relative to the plate 41 within the adjustable distance controlled by the aperture 45. The arm 42 has a spindle 48 fixedly mounted therein for connection with a crank arm 49. The crank arm 49 as illustrated in Fig. 1 has its lower end 50 apertured to receive a threaded connecting rod 51 secured to the crank arm 49 in any selected position by the aid of lock nuts 52. The lower end of the crank arm 51 is pivotally connected at 53 to a rocking element 54 (Figs. 1, 2 and 3). The rocking element 54 is supported between spaced bearings 56 (Fig. 3) on aligned stub shafts 57 carried by the bearings on bracket arms 59 and 60. The bracket arms 59 and 60 are mounted on the main housing 11 of the sanding machine in positions to locate the article feeding mechanism a desired distance from the working surface of the sanding belt.

A counterbalancing unit 62 is provided for the rocking element 54 and the structure mounted thereon and is positioned at the opposite side of the pivotal connection 53 (Fig. 1). The counterbalancing unit includes a threaded bracket 63 which extends inwardly beneath the axis of the rocking element to receive a selected number of weights 64. A table 70 is supported by pantograph links 71 which are mounted upon the rocking element 54. The links 71 are in integral pairs, the links of each pair being joined together by channel members 72. One of the links (Fig. 1) has a downwardly extending leg portion 73 to which the bracket 63 of the unit 62 is secured. A helical spring 74 provides a variable force normally urging the table toward the sanding belt. It will be noted by viewing Figs. 1 and 3 that the spring 74 is disposed concentric with a spindle 75, the axis of which is coincident with the axis of the lower pivotal support for the foremost pair of links 71. One end 76 of the spring 74 extends upwardly and engages the front surface of the adjacent channel member 72, while the other end 77 of the spring 74 is positioned to be received in any one of a multiplicity of notches 78 of a control element 79. The control

element 79 is annular in general contour and is mounted at a fixed position concentric with the spindle 75, the notches 78 being disposed diagonally as illustrated in Fig. 1 to assure locking of the end 77 of the spring against displacement. By adjusting the end 77, clockwise or counter-clockwise, as the case may be, the force in the spring may be decreased or increased depending upon the force desired for moving the article or synthetic crystal against the sanding belt.

A latch 81 pivotally supported at 82 at its inner end to a bracket 83, mounted upon the rocking element 54, has one or more notches 84 in its under surface to receive a pin 85 carried by one of the foremost links 71 to hold the article feeding mechanism, particularly the table 70 thereof away from the belt 14 and in the loading position. A loop-like handle 86 mounted on the front edge of the table 70 is provided for manual movement of the table into its loading position at which time, the latch 81 will fall by gravity when the pin 85 registers with the notch 84.

In the present embodiment of the invention, the article holding means includes a metallic support 88 having suitable means on one face thereof to receive and support a given number of articles or synthetic crystals 89. In the present illustration, cross-bars 90 are formed upon or secured to the surface 91 of the support 88 to support the articles 89. No positive means is provided in the present instance to fix the articles 89 in place. A film of oil or suitable material covers the surface 91 and acts as a retaining means for the articles during the sanding operation. End members 92, having aligned diagonally extending elongate apertures 93 therein, are free to move thereby on supporting screws 94, carried at each side of the support 88. The end members function when in the holding position shown in Fig. 3 to limit movement of the articles 89 during sanding operation. Prior to mounting the support 88 upon the table, that is, when the articles 89 are being loaded on the support, or unloaded therefrom, the support will rest upon its under surface 96 and the end members 92 will be moved to cause the edges 97 thereof to be positioned short of or in a plane with a surface 91.

A magnetic chuck 100 is mounted on the table 70 with its contacting surface 101 positioned short of the leading edge 102 of the table 70, allowing a known distance on the table for mounting of the support 88. A switch 103 mounted in the magnetic chuck 100 may be rotated between given limits to open or close an electrical circuit (not shown) to deenergize or energize the magnetic chuck.

With the distance between the end 101 of the magnetic chuck and the leading end 102 of the table being known, and the thickness of the support 88 also being known, it is possible to control the movement of the articles 89 relative to the sanding belt 14 to cause reduction of the articles to given known dimensions. This is accomplished through the aid of a fixed stop 105 located on a bracket 106 mounted at 107 on the rocking element 54, functioning in combination with a movable adjustable stop 108. The movable stop 108, as well as the fixed stop 105 are formed of hardened steel parts to resist wear. Furthermore, the stop 105 is of a given contour for engagement with the movable stop 108 during arcuate movement thereof with the table 70. An internally threaded element 109 supports the stop 108, this element being mounted upon an adjust-

ing screw 110 which is supported for rotation in an aperture 111 in a downwardly extending portion 112 of the table 70. A knurled wheel 114 mounted on the outer end of the adjusting screw 110 facilitates the manual rotation of the screw to adjust the position of the stop 108 relative to the stop 105. It will be noted by viewing Fig. 4 that the threaded element 109 is supported by a substantially U-shaped member 115, the legs of which have V-shaped grooves 116 disposed in a common plane and positioned to ride on parallel tracks 117 which have V-shaped inner edges receivable in the grooves 116. The tracks 117 are mounted at 118 beneath the table 70. A dial 120 having graduations 121 thereon movable relative to a pointer 122 on the table 70 functions to indicate the final dimension desired for the article being sanded and in this manner will indicate the distance between the surface 91 and the sanding belt controlled by the stops 108 and 105.

During the operation of the article feeding mechanism, it will be noted that the table 70 will be rocked between given limits depending upon the width of the support 88 and the movement desired to cause the articles to traverse substantially the full width of the sanding belt 14. In Fig. 1, the minimum limits are indicated at 125 while the maximum limits are indicated at 126. These limits are determined prior to starting operation of the machine and if variations are desired, they may be accomplished in one instance by loosening the screw 46 and moving the arm 44 about its pivot 43 within the aperture 45 to the desired position. Other variations may be made to center the limits relative to the sanding belt by varying the length of the connecting rod 49-51 through adjustment of the lock nuts 52. These adjustments having been completed, the next adjustment for consideration is the friction clutch shown in Fig. 5 to determine the driving force to be applied in oscillating or rocking the table with the article relative to the sanding belt. By adjusting the screws 34 to vary the forces embodied in the springs 32, the frictional forces created by the clutch members 28 and 29 through their friction elements 30 and 31 on the clutch element 27, may be varied as desired. Another adjustment may be considered before starting the machine. This adjustment includes the spring 74 which determines the force applied through the table to the article in forcing the article against the sanding belt.

In the present illustration, the faces of a plurality of synthetic crystals are being sanded or otherwise ground to correct the surfaces and reduce the thicknesses of the crystals. In other instances (not shown) a plurality of the crystals may be mounted in stacked formation to reduce the lengths or widths of the crystals or articles. In these instances, it may be desirable to increase the force created in the spring 74 and the driving force of the friction clutch. Also the limits of movement of the table may require changing. The final adjustment essential is adjustment of the screw 110, determined by the dial 120 and its graduations 121 moving relative to the pointer 122.

The apparatus is now in condition for operation for successively feeding similar articles to the sanding belt. By suitable means (not shown), a fluid such as water is fed to the sanding belt 14 during the sanding operation. The table 70 is initially in its loading position away from the sanding belt where it is held by the latch 81 engaging the pin 85. A support 88 supplied

with articles 89 in their proper positions is located on the leading end of the table after which the magnetic chuck 100 is energized holding the support in this position. The latch 81 may be released by the operator moving the table to the right (Fig. 3) and then allowing the table to move slowly toward the sanding belt until the articles 89 engage the sanding belt. Operation of the machine continues until the stop 108 engages the stop 105 at which time the sanding operation has been completed.

It should be understood, however, that the pantograph links 71 maintain the table with the articles in a given relation with respect to the path of the sanding belt. The table will at all times lie in a plane perpendicular to the plane of the sanding belt, locating the surface 91 of the support 88 parallel with the plane of the sanding belt. During the continued travel of the sanding belt, the table with the articles are rocked between the selected limits under the driving force governed by the friction clutch. When the operation has been completed, the operator moves the table to the loading position where it is held by the latch 81, after which the magnetic chuck 100 is deenergized, the present support 88 with its articles removed and another support loaded with articles to be sanded positioned upon the table adjacent the chuck 100 held in place by energization of the chuck and then moved into engagement with the sanding belt for a sanding operation on the articles.

The counterbalancing unit 62 performs two important functions in counterbalancing the structure on the rocking element 54, one during operation thereof to rock the table with the article between the selected limits and another to allow the spring 74 to control the force applied to the article in urging it toward the sanding belt. In the first instance, it will be observed that when the table 70 is in the neutral position shown in Fig. 1, the unit 62 is in its neutral position. However, movement of the table in either direction from its neutral position will move the unit 62 a comparable distance in the opposite direction to counterbalance this rocking structure, resulting in a smooth movement of the article relative to the sanding belt. In the second instance, it will be observed by viewing Fig. 2 that the weights 64 of the unit 62 are centrally positioned in a plane with the pivots of the foremost (at the right) pair of links 71 when the links 71 are in their neutral positions shown in this figure and also in Fig. 3. When the latch 81 is released and the spring 74 is free to apply its force to the article, through the links 71, the table 70, the chuck 100 and the support 88, this force would be varied considerably if the structure above the rocking element 54 was not counterbalanced. For example, with the unit 62 removed, movement of the table toward the sanding belt from its neutral position would add a weight-like force to the article, in addition to the force of the spring 74, comparable to the weight of the link 71 and the structure supported thereby. Movement of the table 70 to the right of its neutral position will apply this weight-like force against the force of the spring 74. The unit 62, therefore, counterbalances this weight-like force and allows the spring 74 to apply its selected variable force to the article.

It is to be understood that the above-described arrangements are simply illustrative of the application of the principles of the invention. Numerous other arrangements may be readily de-

vised by those skilled in the art which will embody the principles of the invention and fall within the spirit and scope thereof.

What is claimed is:

1. An article feeding mechanism, for a belt sanding machine having a sanding belt driven through a given plane, the article feeding mechanism comprising a table, means on the table to support an article, parallel links to support the table for movement with the article toward and away from the sanding belt and to maintain the table at a given angle with respect to the said plane through which the belt travels, a spring to apply a predetermined force to one of the links to move the links out of their neutral vertical positions with the table and article toward the sanding belt, and a unit connected to one of the links and positioned to counterbalance the weight force of the links and the structure supported thereby including the table and the article whereby only the predetermined force of the spring will be applied to the article against the sanding belt.

2. An article feeding mechanism, for a belt sanding machine having a sanding belt driven through a given plane, the article feeding mechanism comprising a table, means on the table to support an article, parallel links to support the table for movement with the article toward and away from the sanding belt and to maintain the table at a given angle with respect to the said plane through which the belt travels, a spring to apply a predetermined force to one of the links to move the links out of their neutral vertical positions with the table and article toward the sanding belt, a unit connected to one of the links and positioned to counterbalance the weight force of the links and the structure supported thereby including the table and the article whereby only the predetermined force of the spring will be applied to the article against the sanding belt, a rocking element interposed between the counterbalancing unit and the links to support the links with the table and article for oscillation in a path parallel with the said given plane of the sanding belt, and means to rock the element, the counterbalancing unit also functioning to counterbalance the links and the structure supported thereby during rocking of the element.

3. An article feeding mechanism, for a belt sanding machine having a sanding belt driven through a given plane, the article feeding mechanism comprising a table, means on the table to support an article, parallel links pivotally secured at like ends to the table to support the table for movement with the article toward and away from the sanding belt and to maintain the table at a given angle with respect to the said plane

through which the belt travels, an element mounted at a given position relative to the said plane of the belt pivotally supporting the other ends of the parallel links, a spring to apply a predetermined force to one of the links to move the links out of their neutral vertical positions with the table and article toward the sanding belt, and a weight rigidly mounted on one of the links and centrally positioned in a plane with its pivots to counterbalance the weight force of the links and the structure supported thereby including the table and the article whereby only the predetermined force of the spring will be applied to the article against the sanding belt.

4. An article feeding mechanism, for a belt sanding machine having a sanding belt driven through a given plane, the article feeding mechanism comprising a table, means on the table to support an article, parallel links pivotally secured at like ends to the table to support the table for movement with the article toward and away from the sanding belt and to maintain the table at a given angle with respect to the said plane through which the belt travels, a rocking element pivotally supporting the other ends of the parallel links and mounted for movement about an axis disposed at right angles to the pivots of the links, a spring to apply a predetermined force to one of the links to move the links out of their neutral vertical positions with the table and article toward the sanding belt, and a weight rigidly mounted on one of the links to normally lie in a plane with its pivots and also a vertical plane with the axis of the rocking element whereby, in one instance the weight will counterbalance the weight force of the links and the structure supported thereby including the article to render the spring effective to apply its force to the article against the sanding belt, and in another instance to counterbalance the links and structure supported thereby during rocking movement with the element.
